UNITED STATES PATENT OFFICE

163,147

HAND SPRAYER

Alfred P. Smith, Utica, N. Y.

Application December 20, 1949, Serial No. 6,739

Term of patent 14 years

(Cl. D62—2)

To all whom it may concern:

Be it known that I, Alfred P. Smith, a citizen of the United States, residing at Utica, in the county of Oneida and State of New York, have invented a new, original, and ornamental Design for Hand Sprayer, of which the following is a specification, reference being had to the accompanying drawing, forming part thereof, in which—

Fig. 1 is a perspective view of a hand sprayer, showing my new design, and

Fig. 2 is an end elevation as observed from left of Figure 1.

I claim:

The ornamental design for a hand sprayer, substantially as shown.

ALFRED P. SMITH.
